172,651

FOOD SLICER

Henry J. Talge, Kansas City, Mo., assignor to
John C. Hockery, Kansas City, Mo., trustee for
Henry J. Talge and Foster L. Talge

Application April 9, 1953, Serial No. 24,426

Term of patent 14 years

(Cl. D89—1)

To all whom it may concern:

Be it known that I, Henry J. Talge, a citizen of the United States, residing at Kansas City, State of Missouri, have invented a new, original, and ornamental Design for a Food Slicer, of which the following is a specification, reference being had to the accompanying drawings, forming part thereof, in which:

Fig. 1 is a front elevational view of a food slicer embodying my new design;

Fig. 2 is a side elevational view;

Fig. 3 is a plan view;

Fig. 4 is a rear elevational view; and

Fig. 5 is a side elevational view showing the side opposite that illustrated in Fig. 2.

The essential features of my design reside in the portions shown in full lines.

I claim:

The ornamental design for a food slicer, as shown and described.
